CLAIM

The ornamental design for bottle, as shown and described herein.

DESCRIPTION

FIG. 1 is a top perspective view of a first embodiment of a bottle embodying the new design.

FIG. 2 is a bottom perspective view thereof.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded perspective view thereof.

FIG. 10 is an exploded front view thereof.

FIG. 11 is a top perspective view of a second embodiment of a bottle embodying the new design.

FIG. 12 is a bottom perspective view thereof.

FIG. 13 is a front view thereof.

FIG. 14 is a rear view thereof.

FIG. 15 is a first side view thereof.

FIG. 16 is a second side view thereof.

FIG. 17 is a top view thereof.

FIG. 18 is a bottom view thereof.

FIG. 19 is an exploded perspective view thereof; and,

FIG. 20 is an exploded front view thereof.

The second embodiment is shown with a symbolic break in its length, represented by break lines. The appearance of any portion of the article between the break lines forms no part of the claimed subject matter.

The broken lines in the drawings illustrate the portions of the bottle that form no part of the claimed design.

1 Claim, 18 Drawing Sheets
